CLAIM

The ornamental design for a writing instrument with cap member therefor, as shown and described.

DESCRIPTION

FIG. 1 is a front elevational view of a writing instrument with cap member therefor showing my new design; FIG. 2 is a right side elevational view, the left side being a mirror image thereof;

FIG. 3 is a rear elevational view;

FIG. 4 is a top plan view;

FIG. 5 is a bottom plan view;

FIG. 6 is a perspective view;

FIG. 7 is a front elevational view with the cap member removed for clarity of illustration;

FIG. 8 is a right side elevational view of FIG. 7;

FIG. 9 is a rear elevational view of FIG. 7;

FIG. 10 is a top plan view of the FIG. 7;

FIG. 11 is a bottom plan view of FIG. 7;

FIG. 12 is a front elevational view of the cap member shown separately for clarity of illustration;

FIG. 13 is a right side elevational view of FIG. 12, the left side being a mirror image thereof;

FIG. 14 is a rear elevational view of FIG. 12;

FIG. 15 is a top plan view of FIG. 12; and,

FIG. 16 is a bottom plan view of FIG. 12.
